[57] CLAIM

The ornamental design for a kitchen range, as shown and described.

DESCRIPTION

FIG. 1 is a perspective view of a kitchen range showing my new design; and

FIG. 2 is a front elevational view thereof; and

FIG. 3 is a top plan view thereof.

The rear and bottom walls are substantially plain and unornamented. The side of the device which is not shown is a mirror image of the side disclosed in FIG. 1.
